a corporation of Delaware

Application May 28, 1954, Serial No. 438,058

6 Claims. (Cl. 20—53)

This invention relates to pivoted windows, and more particularly to a pivoted window adapted to engage an expandable frame to effect a weather-tight relationship between the window and the frame.

It is an object of this invention to provide a pivoted window.

It is a further object of this invention to provide a pivoted window made from aluminum, and easily manufactured, and of economical construction.

It is a further object to provide pivoted all-metal windows from extruded metal; and it is another object of this invention to provide a pivoted window, the sash of which is made of extruded aluminum.

It is still another object of this invention to provide a pivoted window having an extruded sash adapted to engage resilient weatherstripping.

It is another object of this invention to provide an all-metal window having a metal sash and expandable frame adapted to compress resilient rubber weatherstripping into weather-tight relationship with said sash.

These and other objects of this invention will become apparent on reading the following descriptive disclosure taken in conjunction with the accompanying drawings, in which:

Fig. 1 is an interior view of the all-metal window;

Fig. 2 is a vertical sectional view parts being broken away taken substantially on line 2—2 of Fig. 1;

Fig. 3 is a transverse sectional view parts being broken away taken on line 3—3 of Fig. 1;

Fig. 4 is a cross section of the frame parts being broken away showing the expandable clamping frame members in open position;

Fig. 5 is a view parts being broken away similar to that of Fig. 4 showing the expandable frame members in closed position;

Fig. 6 is a detailed sectional view of a corner of the frame showing the manner of clamping the expandable frame members;

Fig. 7 is a view taken substantially on line 7—7 of Fig. 6;

Fig. 8 is a sectional view taken substantially on line 8—8 of Fig. 6.

Fig. 9 is a view taken on the line 9—9 of Fig. 1 of the sash showing a double insulating window in outline disposed in the sash;

Fig. 10 is a sectional view of the sash taken substantially on the line 10—10 of Fig. 1 and showing the manner of pivoting the window sash;

Fig. 11 is a sectional view taken substantially on line 11—11 of Fig. 1 and showing the manner of locking the sash to the window frame;

Fig. 12 is a view taken substantially on line 13—13 of Fig. 1 or Fig. 13;

Fig. 13 is a view of the keying mechanism for locking the expandable frame members;

Fig. 14 is a top view broken away in part and partly in section, showing the manner of engaging the key with a coacting worm gear;

2

Fig. 15 is a sectional view of the flexible weatherstripping;

Fig. 16 shows a top view of the window sash rotated through an angle relative to the window frame; and

Fig. 17a is a view taken on the line 17a—17a of Figure 10.

Fig. 17 is a sectional view of the window frame showing the inner expandable U-shaped interlocking members in closed position, and further showing the means for actuating the expandable members to effect said closed position;

Fig. 18 is a view similar to Fig. 17 but showing the inner expandable window frame members in open position;

Fig. 19 is a sectional view looking down upon the means for motivating the end travel links; and

Fig. 20 is a view taken substantially on line 20—20 of Fig. 5.

Referring to the drawings, and particularly Figs. 1 to 3, a window frame adapted to be disposed in a window opening of a wall is provided with an extruded exterior tubular frame piece 1 adapted to be disposed exteriorly to a building wall. A window sill 2 is disposed on the base of the window opening and is separated from the concrete building wall 3 by caulking compound 4.

The sides and top of the window are provided with a U-shaped frame piece 5 adapted to engage the building concrete wall top 6 and the building concrete side walls 7 and 8. An extruded longitudinal metal strip 9 is disposed between the sill of the window and the bottom of the exterior frame piece 1. Extruded longitudinal strips 10 are disposed between the top and the two sides of element 5 and the top and sides of the exterior frame piece 1. A U-shaped sealer tape 11, for example of synthetic rubber, is disposed between the extruded longitudinal members 9 and 10 and the exterior frame piece 1.

As shown in Figs. 2 and 3, the cross section of the exterior frame piece 1 is provided with an integrally united and peripherally disposed L-shaped flange piece 12 adapted to engage the sealer tape 11 in weather-tight relationship. The frame piece 1 is further provided with an integrally and peripherally disposed T-shaped flange piece 13. A plurality of U-shaped longitudinal flange metal strips 14 are secured to the top and bottom of the window opening by conventional means, for example, bolts 15, to a concrete wall structure 16. The said U-shaped members 14 are secured to the said elements 10 through a bracket arrangement of conventional manufacture, generally shown by the numeral 20. A framing plate 17 is disposed on all four sides of the window opening and secured by means of bolt and nut assemblies 18 to the elements 14 and the top of the T-shaped element 13. A plurality of insulating flat plates 19, for example, Micarta plates, are disposed between plates 17 and the T-shaped flange pieces 13. The window frame may also be supplementally supported at its top by means of conventional bracket assembly, generally shown by the numeral 21.

A window sash, generally designated by the numeral 23, Figs. 3 and 12, is made from longitudinal extruded aluminum elements. An exterior tubular longitudinal sash element 23x is provided with an integrally united caulk retaining flange 24. An interior tubular extruded metal sash element 25 is disposed interiorly of the element 23x. The elements 23x and 25 are provided with screw receiving apertures. A plurality of plastic plates, for example, Micarta plates 26, are disposed between the sash elements 23x and 25. A plurality of screws 27 are disposed between the elements 23 and 25 and through suitable apertures located in plastic elements 26.

A removable plate 28 provided with a flanged edge 29 is adapted to be keyed into a coacting groove disposed in the sash piece 25. Removal of the plate pieces 28 pre-

vents removal of the glass window panes 30 from the sash. The removal plate 28 is secured to the inner tubular sash elements 25 by means of a plurality of screws 31 (Fig. 1). The sash 23 is provided at its top and bottom with U-shaped pivot receiving thimbles 32, said thimbles 32 being disposed between the exterior sash element 23x and interior element 25.

A cylindrical pivot pin 33 is centrally disposed in the bottom sash and top sash frame pieces and disposed upon the corresponding T-shaped element 13.

Turning to Figs. 4, 5 and 6, an expandible window frame, generally designated by the numeral 34, consists of four independent U-shaped movable members adapted to be moved toward and away from each other simultaneously as a unit. The four U-shaped members consist of a top U-shaped member 35, a bottom U-shaped member 36, and a pair of lateral U-shaped members 37.

The T-shaped flange 13 of the tubular window frame 1 is provided with a plurality of cam members in the form of slotted flanges 38 at those portions of the flange 13 disposed opposite the vertical movable U-shaped members 37. The slotted flanges 38, Figs. 4 and 5, disposed on opposed sides of the window opening, have angular slots 39 disposed therein. As can be seen from Figs. 4 and 5, the slots disposed on the opposed sides of the window converge toward a common line.

The U-shaped vertical window frame members 37 are provided with a plurality of abutments such as pins 40, which pins are disposed in the opposed legs of the U-shaped member and adapted to engage the slots 39 of corresponding flanges 38.

A pair of corner travel links 41 are secured adjacent the bottom of each of the U-shaped members 37 and adapted to actuate the members 37 selectively upwardly or downwardly. The selective upward and downward motion of the members 37 is modified by the travel of the pins 40 secured to the members 37 so that an inward and outward movement is simultaneously effected with the upward and downward movement due to the travel of the pins 40 in the slots 39.

A hand operated worm wheel 42 (Figs. 17, 18 and 19) is secured to a housing 43. Interiorly of the housing 43 is disposed a worm gear 44 adapted to engage with a co-acting worm gear disposed on worm wheel 42. The worm wheel 42 is provided with a rotatable finger grasp 45 (Fig. 14). The worm gear 44 is connected to a left-handed threaded rod 46 and a right-handed threaded rod 47. The rod 46 is secured to a travel block 48 having a front apertured wall 48a adapted to receive the left-handed threaded rod 46, the lateral sides of which are provided with an inclined ledge 49. An abutment in the form of a rider pin 50 is fixedly disposed in the bottom U-shaped member 36 adjacent the inclined ledge 49 and adapted to be pushed upwardly or downwardly by riding upwardly or downwardly upon the inclined ledge 49. The motion of the pin 50 vertically upwardly or downwardly necessarily causes the U-shaped member 36 to move upwardly or downwardly depending upon the lateral motion of the travel block 48. A threaded left bolt 51 is fixedly secured to the rear wall 52 of the travel block 48. This left bolt 51 is secured to a left hinge block 53.

The right-hand threaded travel rod 47 is secured to a right threaded travel block 54 and having a front threaded apertured wall 55 adapted to receive the right threaded rod 47. The block 54 is also provided with a rear threaded wall 56 adapted to receive the fixedly secured bolt 57, said bolt 57 being in turn removably secured by conventional means, for example, pins 58, to a right hinge block 59. The corner travel levers 41 are secured respectively to the left or right hinge blocks 53 or 59.

A pair of support plates 60 are fixedly secured as, for example, by welding, adjacent the extreme ends of the U-shaped window frame member 36, and are provided with apertures to receive apertured links 61. The links 61 are secured in turn to the respective corner hinge blocks

53 and 59. In the operation of this window to effect movement of the window U-shaped frame members 35, 36 and 37 toward a central point or toward the window sash, rotation of the worm wheel 42 effects rotation of the worm gear 44, which gear 44 is in turn fixedly secured both to the left-handed threaded travel rod 46 and to the right-handed threaded travel rod 47. This rotation of the worm gear 44 causes the travel blocks 48 and 54 to simultaneously move inwardly or outwardly, depending on the direction of rotation of the worm gear 44. In other words, the threaded rods 46 and 47 cause movement of the travel blocks 48 and 54 toward or away from the fixed yoke 43. The movement of the blocks 48 and 54 causes movement of the respective corner hinge blocks 53 and 59, and since these hinge blocks are linked by means of the parallel travel links 44 to the vertical U-shaped window frame members 37, it follows that lateral movement of the blocks 53 and 59 affects a vertical movement of the frame members 37, which vertical movement of the frame members 37 is modified in part to a lateral movement due to the sliding effect of pins 40 in slots 39 of the flanges 38, which slots act as cam members.

Simultaneously with the movement of the blocks 48 and 54, the inclined ledge 49 of the travel block 48 causes the pin 50 to ride upwardly or downwardly so that the bottom U-shaped window frame member 36 is accordingly moved upwardly or downwardly. This upward and downward movement of the bottom frame member 36 is assisted by the movement of the links 61 so that the closing effect of the frame member 36 against the window sash is firm and positive.

In order to affect a downward and inward movement of the top frame member 35 simultaneous with an upward and inward movement of the bottom frame member 36, the U-shaped frame members 37 are linked to the frame member 35 by means of a pair of right angle plate pieces 62. The plate pieces 62 are fixedly secured along one leg to their respective U-shaped frame members by conventional means, for example, rivets 63. The other leg of the right angle plate pieces 62 is provided with slots 64.

A pair of spaced apart blocks 65 are fixedly secured, for example, by metal screws 66, to the top T-shaped flange 13 of the corresponding top section of the frame piece 1. The blocks 65 are provided with an inclined face 67 disposed respectively away from the pivot pins 35. A movable block 68, having a tapered or inclined top face 69, is disposed adjacent the block 65 with the face 67 of block 65 slidingly engaging the face 69 of travel block 68. Blocks 68 and 69 serve as cooperating cam members.

The travel block 68 is provided with a rod 70 securely disposed in an aperture in block 68. The rod 70 (Fig. 20) is provided at its free or unsecured end with an end block 71 having a longitudinal slot 72 therein, the axis of the slot being disposed linearly with the rod 70. A pin 73 is disposed within the slots 64 of the parallel plate pieces 62 at each corner of the window frame and through the slot 72 of the end block 71.

The loose arrangement of pin 73 within the slots 64 permits an upward movement of U-shaped window frame member 35 with a simultaneous upward and outward movement of lateral U-shaped window members 37. Clearly, therefore, the motivating mechanism of this invention shown in Figs. 4 and 5, and showing the movable U-shaped window frame members in open position (Fig. 4) and closed position (Fig. 5), affects an upward and downward movement of the top and bottom U-shaped frame members 35 and 36, and a corresponding movement of the members 37.

A continuous peripheral weather strip 74, having the preferred configuration shown in Fig. 15, is secured in the window frame piece exteriorly of the movable U-shaped window frame members 35, 36 and 37. Apertures are provided in the continuous weather strip 74,

both at the top and bottom thereof, to permit passage of the pivot pin or rod 33 therethrough.

The weather strip 74 (Fig. 2) is clamped to the exterior tubular frame pieces 1, and the corresponding interior elements 17, by means of longitudinal T-shaped clamping plates 75 disposed securely to both edges 76 of the weather strip 74. Clearly, therefore, when the window sash 23 is disposed within the circumferentially and peripherally disposed weather strip 74 (Fig. 2), simultaneous actuation of the U-shaped window frame movable members 35, 36 and 37 causes an inward movement of the corresponding sections of the weather strip 74 to affect a firm weather-tight seal between the weather strip 74 and corresponding ridges 77 of the sash 23. In order to affect a locking of the window sash 23 in place relative to the window frame, the sash is provided with a pair of hinge lock bars 78 (Figs. 1 and 11).

The lateral U-shaped members 37 are provided with slots 79 to permit travel of the locking bar 78 therein and to engage the fixedly disposed lock pin 80 disposed between the legs of the U-shaped member 37. The lock pin 78 is provided with a slot, not shown, adapted to engage the lock pin 80 in locking relationship. The lock pin 78 is disposed centrally within the sash 23 (Fig. 11) and adapted to be rotated through an arc by means of a key (not shown), adapted to engage a rotatable barrel 81. The pin 78 is keyed to the rotatable barrel 81 by means of an insertable key 82, fixedly disposed between the barrel 81 and the locking bar 78. The barrel 81 is disposed in an apertured sash cylinder 83, and is provided with ends adapted to engage a key from either side so that the window may be opened from the interior of the building or from the exterior of the building, as by firemen in case of fire.

In order to prevent pinching of the weather strip 74 at the corners of the movable U-shaped frame members 35, 36 and 37, a plurality of freely slidable U-shaped corner elements 84 are disposed in each of the four corners between the respective movable U-shaped elements and the weather strip 74. Clearly, the weather strip 74 is not clamped to the window frame members at the corners so that there is free sliding movement of the corners 84 against the base of the corresponding U-shaped members.

As shown in Figure 10, the tubular sash members 23 and 25 may be provided with filler block 85, for example, soft metal or equivalent material, and screws 86 are used to secure the filler block 85 in place about the thimble 32. The use of the filler block 85 affects a rigid strong construction about the thimble 32, which thimble supports the weight of the sash.

As shown in Fig. 15, the weather strip 74 is provided with a pair of parallel disposed circular apertured pressure engaging sections 87 adapted to engage the pressure ridges 77 of the sash.

While this invention has been described by means of a single embodiment, it will become apparent to those skilled in the art that the generic scope of this invention embraces all window frames having peripherally disposed resilient weather strips motivated by pressure bars disposed about said peripherally and circumferentially disposed weather strip.

Having described our invention, what we claim and desire to secure by Letters Patent is as follows:

1. A pivoted window structure comprising a sash, a hollow frame having top, bottom and side hollow frame members, means for pivoting the sash at opposite points to the frame, opposed side sash sealing bars, top and bottom sealing bars within the frame, reversely movable actuating members carried in the bottom hollow frame member, means for simultaneously moving said actuating members in reverse directions, links connected to said reversely movable actuating members and pivotally connected to the bottom sealing bar near the ends thereof, an abutment carried by said bottom sealing bar, a cam

carried by one of said reversely movable actuating members for engagement with said abutment, levers carried by said reversely movable actuating members at the ends thereof and connected to the side sealing bars for moving them upwardly and downwardly, a plurality of cam devices within the side members of the hollow frame and connected to the side sealing bars for moving them inwardly and outwardly in accordance with their upward and downward movements, link and cam connections between the side sealing bars and the top sealing bar.

2. A pivoted window structure constructed in accordance with claim 1, in which each of the side member cam devices comprises a plurality of spaced cam members within the side hollow frame members, and cam engaging abutments carried by the side sealing bars for engagement with said cam members.

3. A pivoted window structure constructed in accordance with claim 1, in which the reversely movable actuating members within the hollow bottom frame consist of rods reversely threaded at one end, said means for simultaneously moving said actuating members comprising a worm having reversely threaded interior apertures for receiving said rods, manually operated means for rotating said worm, and connections between the end of each rod and one of the links and one of the levers.

4. A pivoted window structure constructed in accordance with claim 1, including side clamping bars and a top clamping bar in which the link and cam connections between the side sealing bars and the top sealing bar consist of plates, one connected to each side clamping bar near the top thereof and having an angular extension extending longitudinally of the top clamping bar, two cam members each having connection with one of said plates for sliding movement, and co-acting cam members, said co-acting cam members being fixed within the hollow top frame member and each adapted to be engaged by one of said first named cam members.

5. A pivoted window structure comprising a sash, a hollow frame, means for pivoting the sash at opposite points of the frame, opposed side sash sealing bars, top and bottom sealing bars within the frame, means linking said sealing bars, means including cam devices for simultaneously moving said sealing bars outwardly from and inwardly toward said sash, and resilient means carried by said frame and disposed exteriorly of said sash sealing bars for effecting a weathertight seal of the sash in the frame, said resilient means comprising a flexible strip adapted to engage the peripheral surfaces of the sash, said strip having two flanged edges and being retained in position by T-shaped clamping plates engaging securely said flanged edges, said frame having longitudinally channeled portions at either side of each sealing bar, adapted to receive said strip edges and the leg portions of said clamping plates, and said strip edges and frame surfaces adjacent said channels being adapted to interfit with the cross-portions of said plates.

6. A pivoted window structure comprising a sash, a hollow frame, means for pivoting the sash at opposite points of the frame, opposed side sash sealing bars, top and bottom sealing bars within the frame, means linking said sealing bars, means including cam devices for simultaneously moving said sealing bars outwardly from and inwardly toward said sash, and resilient means carried by said frame and disposed exteriorly of said sash sealing bars for effecting a weathertight seal of the sash in the frame, said resilient means comprising a flexible strip adapted to engage the peripheral surfaces of the sash, said strip being retained in position independently of the sash by means applied to the marginal edges thereof, said frame being U-shaped for receiving the sealing bars, and having walls adapted to receive said strip margins.
